UNITED STATES PATENT OFFICE.

EDWARD A. DAY, OF ODANAH, WISCONSIN, AND ALEXANDER W. WHITE, OF ROBERTVILLE, NEW BRUNSWICK, CANADA.

AMUSEMENT APPARATUS.

1,407,642.

Specification of Letters Patent. Patented Feb. 21, 1922.

Application filed January 25, 1921. Serial No. 439,783.

To all whom it may concern:

Be it known that we, EDWARD A. DAY and ALEXANDER W. WHITE, citizens, respectively, of the United States and Canada, 5 and residents, respectively, of Odanah, in the county of Ashland and State of Wisconsin, and Robertville, in the county of Gloucester, Province of New Brunswick, and Dominion of Canada, have invented a new 10 and Improved Amusement Apparatus, of which the following is a full, clear, and exact description.

This invention relates generally to the class of amusement apparatus and has particular reference to a device which is designed to test the skill of a contestant, in maintaining his equilibrium during the 15 operation of the same.

The invention primarily contemplates the provision of an apparatus which when in use, closely simulates the usual log rolling contests, which at present consist in attempts of the contestants to balance themselves on a log placed in a body of water.

25 A further object of the invention is to provide a device of the character described which is comparatively simple in construction, inexpensive to manufacture and which is strong and durable in its structure.

30 With the above recited and other objects in view, some of which will appear more clearly as the nature, purpose and operation of the invention are better understood, reference is had to the following specification, 35 the appended claims and the accompanying drawings, in which;

Figure 1 is a front elevation of the device.

Figure 2 is a side view thereof.

40 Figure 3 is a fragmentary sectional view taken approximately on the line 3-3 of Figure 2.

Referring to the drawings by characters of reference, a supporting frame is provided which includes a base comprising a longitudinal beam 10 mounted on transverse beams 11. A pair of vertical standards 12 are secured to the longitudinal beam 10, the same being preferably constructed of tubular pipe sections received at their lower ends 45 by the members 13 which are secured to the longitudinal beam 10. A cylindrical member 14 simulating a log is yieldably supported at its opposite ends by the standards 12 for axial rotation on a horizontal axis. The 50 supporting means here illustrated comprises

annular end plates 15 each provided with trunnions 16 which are secured by suitable fastening elements 17 to the opposite ends of the cylindrical member. The trunnions are adapted to be received by the annular 60 bearing members 18 having a depending apertured lug 19 which is received between the apertured furcations of a bifurcated bracket 20 through which a pivot pin or bolt 21 is passed for connecting the bearings and 65 bracket together. The brackets 20 are each provided with a depending circular shank 22 which is designed to be telescopically received by the upper extremities of the standards 12. In order to provide means for 70 yieldably supporting the cylindrical member 14 from the standards, a coiled expansion spring 23 is arranged within the standards and the upper end of said springs bear directly against the lower ends of the 75 shanks 22.

In use of the apparatus, the contestants mount the cylindrical members 14 and attempt to rotate the same with their feet while in a standing position, at the same 80 time endeavoring to maintain their equilibrium. The yieldable body 14 closely simulates the action of a log placed in a body of water, in that the pivotal connection between the bearing members 18 and the 85 brackets 20, permit of independent vertical movements of the opposite ends of said cylindrical body.

Where the cylindrical member 14 is disposed an appreciable distance above the 90 ground or floor level, it is desirable for the safety of the contestants, to arrange therebeneath a safety net 25. As illustrated said safety net is supported on the upper ends of the vertical standards 26, the lower ends of 95 which are received by the members 27 which are secured adjacent the opposite ends of the transverse beam 11. Brace rods 28 are provided for each standard 26, the same being secured respectively in the eyes 29 and 100 30 which are provided on the standards and the transverse beams. The opposite ends of the brace rod are reversely threaded as at 31 and receive the turn buckles 32 for the purpose of adjustments. In connection with the 105 device any suitable platform or platforms may be used and arranged at the opposite ends of the cylindrical member 14 together with suitable ladders for the purpose of gaining access thereto.

2

While there has been illustrated and described a single and preferred embodiment of the invention, no limitation is necessarily made to the precise structural details which 5 may be varied in so far as they fall within the scope and meaning of the appended claims.

We claim:

1. An amusement apparatus including a 10 cylindrical member and vertically yieldable means for rotatably supporting the same at its opposite ends to permit of independent vertical movements of the extremities thereof, whereby the cylindrical member will 15 simulate the action of a log in water.
2. In an apparatus of the character described, a substantially cylindrical member having trunnions at the opposite ends there-

of, a frame including vertical standards, brackets yieldably carried by the upper ends 20 of said standards and bearing members adapted to receive said trunnions, pivoted to said brackets, as and for the purpose specified.

3. An amusement apparatus, comprising 25 a substantially cylindrical member having concentric trunnions at its opposite ends, a supporting frame including standards, vertically yieldable members carried thereby, and bearing members receiving the trunnions and pivoted to the vertically yielding bearing members, as and for the purpose specified.

EDWARD A. DAY.
ALEX. W. WHITE.
